(57) **CLAIM**

The ornamental design for a culture tray, as shown and described.

DESCRIPTION

1. Culture tray

1.1 : Perspective

1.2 : Front

1.3 : Back

1.4 : Top

1.5 : Bottom

1.6 : Left

1.7 : Right

1.8 : Partial enlarged perspective view

1.9 : Partial enlarged perspective view

1.10 : Partial enlarged top view

1.11 : Partial enlarged top view

1.12 : Partial enlarged top view

1.13 : Partial enlarged cross-sectional view

1.14 : Partial enlarged cross-sectional view

1.15 : Partial enlarged cross-sectional view

1.16 : Partial enlarged cross-sectional view

1.17 : Reference view showing the state in use

1.18 : Reference view showing the state in use

The present article is a tray for culturing cells that is covered with film when used; reproduction 1.13 is a partial enlarged cross-sectional view sectioned horizontally at the center of the top view; reproduction 1.14 is a partial enlarged cross-sectional view sectioned horizontally at the center of the top view; reproduction 1.15 is a partial enlarged cross-sectional view sectioned vertically through the injection/extraction part; reproduction 1.16 is a partial enlarged cross-sectional view sectioned vertically through the projections beside the injection/extraction part.

(Continued)

The broken line showing of portions of the culture tray is for the purpose of illustrating environment and forms no part of the claimed design.

1 Claim, 18 Drawing Sheets**(58) Field of Classification Search**
